UNITED STATES PATENT OFFICE.

WILLIAM REID, OF PHILADELPHIA, PENNSYLVANIA.

GARMENT HANGER.

Application filed March 11, 1924. Serial No. 698,395.

To all whom it may concern:

Be it known that I, WILLIAM REID, a citizen of the United States, residing at Philadelphia, county of Philadelphia, and 5 State of Pennsylvania, have invented certain new and useful Improvements in Garment Hangers, of which the following is a specification, reference being had to the accompanying drawings.

10 This invention relates to garment hangers and is directed to the provision of a hanger that may be used either for double point suspension as in wardrobe trunks, or for single central point suspension when employed in closets, and so designed that it may be transferred between a trunk and a closet without disturbing the garments thereon.

This desideratum I attain through a very 20 simple arrangement in the form of an attachment that can be applied to a hanger characterized by a cross bar above the coat hanging portion through aid of which the hanger is ordinarily supported by parallel 25 rods in a wardrobe trunk. This attachment comprises a yoke to span the cross bar so as to leave the same free for skirt or trouser hanging, said yoke being provided with a central suspension hook, and capable of 30 folding to a position within the perimetrical confines of the hanger so as to be entirely out of the way when not in use. With the attachment are associated means which will firmly hold it in either the unfolded or 35 folded position, yet permit movement, with expenditure of a very slight effort, when conversion is to be effected to one or the other condition of use.

The practical advantages accruing from 40 my invention will be readily appreciated from the detailed description which follows of a typical embodiment thereof, the appended claims serving to point out clearly and precisely the features which I believe to be new and novel and therefore patentable.

In the drawings, Fig. I is an illustration 45 showing my improved garment hanger in side elevation with the means whereby the same may be converted for single point suspension in out of use position.

Fig. II is a similar view of the hanger with the means aforesaid in service position; and

55 Fig. III is a detail view in perspective

showing one of the parts of the conversion means on a larger scale than in Figs. I and II.

Referring first to Figs. I and II of these illustrations, it will be observed that the 60 garment hanger comprises a coat hanging portion 1 which is substantially arcuate in configuration, and an overlying horizontal skirt or trouser hanging cross bar 2 joined to the portion 1 by a comparatively narrow 65 vertical connecting web 3, the cross bar having notches 4 cut in its lower edge near its ends designed to engage parallel bars or rods such as ordinarily found in wardrobe trunks for two point suspension of the hanger. 70 Such a hanger structure may be readily fabricated from wood, or formed from appropriate sheet metal by die stamping.

The means whereby the hanger may be converted for central single point suspension includes a yoke or bail 5 preferably formed of comparatively stout wire characterized by a certain amount of flexibility for a purpose to be presently explained. The longitudinally extending segment 6 of 80 the bail 5 is angularly offset slightly at the center as indicated at 7, and there provided with a suspension hook 8. Near its extremities the wire of the bail 5 is perpendicularly bent to provide short spacing segments 9, 85 and beyond these again bent into parallelism with the longitudinal segment 6 to form terminal trunnions 10. Adjacent the ends of the cross bar 2 are attached plates 11 one of which is shown in complete detail 90 in Fig. III of the drawings. These plates 11 may be conveniently made as die stampings rectangular in outline with corner holes 12 for screws or other convenient attachment means 13 (Figs. I and II), and formed 95 with integral outstanding pivot ears 14 to take the trunnion ends 10 of the wire bail 5, as well as offset lugs 15 adjacent the ears, said offsets providing recesses for engaging the spacing segments 9 of said bail. With 100 this construction it will be apparent that the bail 5 may be swung about the aligned axes of its pivotal attachment with the cross bar 2 of the hanger either to the folded position of Fig. I, or to the extended or 105 unfolded position of Fig. II. The bail 5 is held in either of these positions through the engagement of the spacing segments 9 with the recessed lugs 15 of the plates 11 yielding maintained through the inherent 110

springiness of the wire, release of this engagement to permit turning being readily accomplished by a very light effort applied to expand the bail 5 sufficiently lengthwise (as possible by reason of the angular offset 7) as shown in dotted lines in Fig. I to release the spacing segments 9 aforesaid from the recesses of the lugs 15.

Attention is particularly directed to the fact that by virtue of its configuration, the bail 5 when in the collapsed position of Fig. I lies directly against one side of the hanger and wholly within the perimetrical confines of the latter so as to be entirely out of the way when not in use, i. e., when the hanger is to be supported by the cross bar 2. Furthermore the possibility of anything being caught by the suspension hook 8 of the bail 5 when in collapsed position is obviated by inclusion of said hook within the area of the web 3 that connects the arcuate coat supporting portion 1 of the hanger with the cross bar 2.

When the bail 5 is swung to the extended position of Fig. II for support of the hanger by the hook 8, it will be noted that said bail spans substantially the entire length of the cross bar 2 leaving the same unobstructed for hanging of skirts or trousers as before with a sufficient interval above its upper edge to permit ready threading of such garments in the course of their application to the hanger.

The garment hanger of my invention is particularly advantageous and convenient for travellers since by reason of its susceptibility to conversion, as hereinbefore explained, it may be suspended from ordinary closet hooks or on the parallel supporting bars of standardized wardrobe trunks. The transfer of the hanger between a closet and a trunk may be effected without disturbing the garments hung thereon, as the hook 8 of the bail 5 has a clear path for swinging in either direction through the open neck portion of a supported coat.

Having thus described my invention, I claim:

1. A garment hanger with provisions enabling it to be supported from opposite ends, and auxiliary attached means yieldingly hinged to the hanger whereby the same may be converted for central single point suspension.

2. A garment hanger with provisions enabling it to be supported from opposite ends, and auxiliary attached means whereby the hanger may be converted for central single point suspension, said means being yieldingly hinged for containment within the perimetrical confines of the hanger so as to be entirely out of the way when not in use.

3. A garment hanger formed with a cross bar engageable at opposite ends to support the hanger, in combination with a yield-

ingly trunnioned bail foldable on the hanger whereby the same may be converted for central single point suspension.

4. A garment hanger formed with a substantially arcuate coat-hanging portion and a cross bar above said portion engageable at opposite ends to support the hanger, and a yieldingly trunnioned bail whereby said hanger may be converted for central single point suspension, said bail being foldable to a position within the perimetrical confines of the hanger so as to be entirely out of the way when not in use.

5. A garment hanger with provisions enabling it to be supported from opposite ends, and a flexible bail attached to the hanger whereby the same may be converted for central single-point suspension, and means for yieldingly maintaining the flexible suspension bail in either the unfolded or folded position.

6. A garment hanger having a substantially arcuate coat hanging portion with an overlying cross bar joined by a narrow vertical web to said portion and engageable at opposite ends to support the hanger, in combination with means whereby the hanger may be converted for single central point suspension including a yieldingly trunnioned bail swingable downwardly in retained position against the web aforesaid so as to be entirely out of the way when not in use.

7. A garment hanger with a substantially arcuate coat hanging portion and an overlying cross bar engageable at opposite ends to support the hanger, in combination with means whereby the hanger may be converted for single point suspension including a bail formed with a central hook and attached at its extremities to the ends of the cross bar to leave the latter clear of obstruction for trouser or skirt hanging, said bail being foldable to a position within the perimetrical confines of the hanger so as to be entirely out of the way when not in use.

8. A garment hanger with a substantially arcuate coat hanging portion and an overlying cross bar engageable at opposite ends to support the hanger, in combination with means whereby the hanger may be converted for single point suspension including a bail of flexible wire formed with a central hook and having its extremities pivotally attached to the ends of the cross bar to leave the latter clear of obstruction for trouser or skirt hanging, said bail swingable downwardly to a position within the perimetrical confines of the hanger so as to be entirely out of the way when not in use, and means with which the bail is yieldingly maintained in engagement under its inherent springiness to keep it in either the unfolded or folded positions.

9. A garment hanger with a substantially arcuate coat hanging portion and an over-

lying cross bar engageable at opposite ends to support the hanger, in combination with means whereby the hanger may be converted for single point suspension including a bail of flexible wire formed with a central hook, means whereby the extremities of the bail are attached to the ends of the cross bar so as to leave the latter clear of obstruction for skirt or trouser hanging, said means comprising plates with integral ears for pivotally engaging trunnions formed at the ends of the bail whereby the latter may be swung downwardly to a position out of the way within the perimetrical confines of the hanger when not in use, and recessed lugs also integrally formed on said plates with which angularly-turned portions at the bail extremities are maintained in engagement under the inherent springiness of the

wire to keep the bail in either the extended 20 or collapsed position.

10. A garment hanger with a substantially arcuate coat hanging portion, an integral cross bar above said portion having undercut notches at opposite ends to support 25 the hanger, a bail pivotally trunnioned to the cross bar so as to leave the latter clear of obstruction for skirt or trouser hanging, and a hook centrally of the bail providing a single point suspension for the hanger. 36

In testimony whereof, I have hereunto signed my name at Philadelphia, Pennsylvania, this 6th day of March, 1924.

WILLIAM REID.
